[57] CLAIM

The ornamental design for extended welded metal section for an I-beam structure, as shown and described.

DESCRIPTION

FIG. 1 is an end view of the extended welded metal section for an I-beam structure;

FIG. 2 is a view of the other end to that of FIG. 1;

FIG. 3 is a bottom view of the extended welded metal section for an I-beam structure;

FIG. 4 is a top plan view from above;

FIG. 5 is a right side elevational view thereof;

FIG. 6 is a left side elevational view thereof; and,

FIG. 7 is a perspective view of the section shown in FIG. 6.
